INVENTOR,
Grant Sipp.

BY HIS ATTORNEY

TORNEY
John D. Lewis

UNITED STATES PATENT OFFICE

GRANT SIPP, OF PATERSON, NEW JERSEY, ASSIGNOR TO SIPP-EASTWOOD CORPORATION, OF PATERSON, NEW JERSEY, A CORPORATION OF NEW JERSEY

WARPING MACHINE

Application filed March 30, 1932. Serial No. 601,922.

This invention relates to warping machines and particularly so-called Swiss warping machines in which the warp is wound on the reel in sections in substantially this manner, to wit: As each section is wound on the reed-carriage is traversed a given distance in one direction parallel with the reel axis, so that the section is laid on the reel spirally, and when the next section is wound the reed-carriage is first set back a distance equal to its traverse plus the section width, and so on, so that the first convolution of each section will be on the reel and the remaining convolutions of each section but the first will be on the convolutions of the preceding section, it being understood that all the sections are cut, on each being wound, the same length so that their outer ends are all free and all may therefore be unwound, as in the ensuing beaming operation, at once.

In winding the warp on the reel the warper has to be notified for placing certain visible indications for use in reference to the particular weaving operation, that is to say, lease cords and "cut-marks" (as by chalking at points at which the warp is to be divided, for instance, each 100 yards, if the warp for a given loom is to have that length); in addition he has to be notified when the limit of a predetermined length of the entire warp as prepared in the warping has been reached, it being understood that such includes in its length enough for two or more weaving operations.

Warping machines usually have a "clock" which indicates when the warper should attend to these indications, as in my Patent No. 1,756,217. The rotary dial of this clock has a number of studs or "actuators" which are settable circumferentially to arbitrary positions, as the stud 25 in said patent.

What I contemplate by the present improvements is to facilitate the manipulations incident to the adjustment of these actuators, thus saving time and insuring against mistakes on the part of the warper.

The drawings show in

Fig. 1 is side elevation of a warping machine embodying the invention;

Fig. 2 an enlarged side elevation of the

clock and mechanism cooperative therewith;

Fig. 3 a still larger fragmentary elevation of parts of the clock as seen from the opposite side;

Figs. 4 and 5 one of the actuators and its button, the latter in two different positions and parts of means to be energized;

Fig. 6 a section on line 6-6, Fig. 4;

Fig. 7 a section on line 7-7, Fig. 3;

Fig. 8 a perspective view of a certain "clip"; and

Fig. 9 a plan of a certain circuit contact device.

At 1 is the reel journaled in the frame 2 and having the staves 3 on which the sections are wound. At 4 is a suitably guided member forming a part of stopping means and which when depressed causes stopping of the machine as fully disclosed in my aforesaid patent. Any equivalent member which when moved causes, by actuating appropriate mechanism, stopping of the machine may of course be utilized.

Or instead of stopping the machine thus automatically, it may be stopped by the operator himself when a special signal device is actuated; or this signal device may be used with the automatic stopping. Such device may be one of two electric lamps 5-5a in the branches of a conductor 6 containing a battery or equivalent source of electric energy 6a and at the terminals of its branches the elastic contacts 7-7a mounted on an insulating block 8 which may be attached to some part of the fixed structure of the machine (as the bracket 9 to be mentioned), the electric circuit when established being completed by the metal frame of the machine to which the unbranched end of the conductor is attached and the rotary metal member of the clock journaled in the metal part of the fixed structure.

Said part of the fixed structure is a bracket 9 upstanding from the frame and equipped with a fixed pointer 10. The rotary member of the clock is a dial 11 which is connected to rotate with the reel by the following parts: A rotary shaft 12 is geared with the peripheral teeth of the dial as shown in Fig. 2 and with a bevel gear 13, whose shaft is sprocket-

and-chain-driven, as at 14, from the reel shaft. So much is substantially the same as in my said patent and requires no more detailed description; so also is the cross-sectionally T-shaped circumferential groove 15 forming a guideway in the far face of the dial, which has index markings at 16 with reference to which the pointer cooperates.

In the groove are arranged a number of 10 studs or supports 18. Each of these includes a square head 18a in the wide part of the groove and a shank 18b projecting therefrom through the slot or narrow part of the groove, this shank being outward of the dial threaded 15 at 18c, formed with spaced stops 18d, and between the stops with two spaced circumferential grooves or notches 18e 18f. The stud also includes, screwed on its threading, a nut 20 which may coact with the head 18a 20 to clamp the stud to the dial. Between the nut and dial is a pointer-device 21, which is a pointed plate formed with two lugs 21a which engage in the groove to keep the device from turning from its normal position 25 (with its point projecting radially inward when the clamping action of the stud is relaxed) as when the stud is to be shifted in the groove.

On the shank of the stud is a roller or 30 revoluble button 22 formed with a head 22a and a circumferential knob 22b having a circumferential notch and in the plane thereof a slit 22c which extends to the bore of the button. The notch receives a circular spring 35 23 one end 23a of which is bent inward in a chord to occupy the slit. The spring thus forms a slip-clutch, its part 23a being adapted to engage in either notch 18e or 18f so as to hold the button against endwise displacement, though releasably.

With the nuts 20 detached the studs are entered into groove 15 through a hole 24, Fig. 2, in the dial.

Assume that the entire warp length is to 40 be 400 yards, as to which the warper himself requires notice in winding each section when that length or cut-off point has been reached; further, that each 100 yds. in the entire length the user of the warp requires visible 45 indication, or a "cut-mark" (as a chalk-mark), for cutting the length into warps for four different weaves; and further that in each such weaving warp, or fragment of the entire length, the user required in each section thereof lease-cords to maintain leases or crosses (which the warper forms therein), the several lease cords for the different sections being alined across the warp.

50 For the first of these an actuator (each stud and button) is secured in the dial at the 400 mark or cut-off point; for the second, other actuators are secured at the 300, 200 and 100 marks or "cut-marks"; and for the 55 third other actuators are secured between 0

and 100, 100 and 200, and so on, for the leasing points.

When the first section is wound all the buttons of the indicated actuators are pushed inward, as in Fig. 5, so that on the rotation 70 of the dial with the reel the buttons will one after another engage the member 4 to stop the machine, the warper at each stop at or between the 100—200—300—400 marks marking the section with a "cut-mark" or inserting a lease-cord in the cross he then forms, as the case may be, except at the 400 mark, where he cuts off the section. When the next section is wound he withdraws all the buttons except those corresponding to the leasing 75 points and the 400 or cut-off mark, so that the withdrawn buttons will miss (Fig. 4) the member 4. Hence stopping will be effected only by those buttons left inward, i. e., for stopping at the leasing point and also the 80 400 mark where the section is to be cut off; the lease-cords, it will be understood, have to be in the entire width of the warp, but "cut-marks" will serve the user if they are only 85 applied to the first section, and so it is not desired to stop the machine at these points except for the first section. This last arrangement of the buttons remains until all 90 the sections which are to comprise the warp are wound on the reel. (Of course when each section is fully wound and cut off at the 400 mark the dial is turned back independently of the reel to the starting point, or where 0—not shown—coincides with the pointer 10; this 95 may be done by sliding the dial axially out of gear with element 12 or in any other way—a matter which is not here material.)

100 In a sense we may properly regard the stopping means of which the element 4 forms a part as a signalling means in that when stopping occurs it signifies to the warper that he has one of the indicated duties to perform. However, it may be desired to afford him some special signal, in which case the described electrical signal-including means 105 may be used as follows:

110 For the winding of the first section those buttons which are to indicate the lease-cord points and the final cut-off point are pushed fully in so that their heads will coincide with the contact 7 (their slip-clutches being engaged at 18e) and the remaining buttons, for indicating "cut-marks", are positioned so that 115 their heads will coincide with the contact 7a (their slip-clutches being engaged at 18f). For the winding of each succeeding section the latter buttons are withdrawn against the outer stop 18d (dotted lines, Fig. 5). (The two signal-lamps may be differently 120 colored so as to distinguish the "cut-mark" stops from the others.) Of course only one contact, as 7, and one signal device may be used, if desired, when the general operation 125 would be substantially the same as where 130

the stopping means including member 4 is employed as a signal.

Broadly my invention contemplates the provision of supports (as 18) on the dial each 5 settable to different positions circumferentially thereof and all affording guideways (as 18b) which in any position to which the supports are set extend in generally the same direction (or here parallel, because they 10 parallel the axis of the dial), a signalling means to be energized having the part to which the signalling energy is transmitted arranged laterally of the guideways, and a button on each support movable along its 15 guideway into and out of position to engage said part.

Having thus fully described my invention what I claim is:

1. In combination, a rotary reel on which 20 the material to be wound is wound, a dial connected to rotate with the reel, supports on the dial each settable to different positions thereon circumferentially thereof and all affording guideways which in any position 25 to which the supports are set extend in generally the same direction, a signalling means to be energized having the part thereof to which the signalling energy is transmitted arranged laterally of the guideways 30 of said supports, and a button on each support movable along its guideway into and out of position to engage said part and thus energize said means on rotation of the dial.

2. In combination, a rotary reel on which 35 the material to be wound is wound, a dial connected to rotate with the reel, supports on the dial each settable to different positions thereon circumferentially thereof and all affording guideways which in any positions to 40 which the supports are set extends substantially parallel with the dial axis, a signalling means to be energized having the part thereof to which the signalling energy is transmitted arranged laterally of the guideways 45 of said supports, and a button on each support movable along its guideway into and out of position to engage said part and thus energize said means on rotation of the dial.

3. In combination, a rotary reel on which 50 the material to be wound is wound, a dial connected to rotate with the reel, a support device on the dial having a guideway and settable to different positions thereon circumferentially thereof with its guideway extending 55 in the same direction, a signalling means to be energized having the part thereof to which the signalling energy is transmitted arranged laterally of the guideway of said support, and a button device on the support 60 device movable along the guideway into and out of position to engage said part and thus energize said means, one of said devices having a notch and the other a slip-clutch to engage the notch when the button device is 65 in one of said positions.

4. In combination, a rotary reel on which the material to be wound is wound, a dial connected to rotate with the reel, supports on the dial each settable to different positions thereon circumferentially thereof, a signalling means to be energized, and devices on the respective supports each movable on its support into and out of position to engage and thus energize said means without disturbing the position to which such support is set. 70 75

In testimony whereof I affix my signature.
GRANT SIPP.
